UNITED STATES PATENT OFFICE

2,578,494

ELECTRIC SWITCH

Harry Shaw Wiggins, Long Beach, Calif.

Application May 27, 1949, Serial No. 95,714

1. Claim. (Cl. 200—153)

1

This invention relates to new and useful improvements and structural refinements in electric switches, and the principal object of the invention is to greatly simplify the switch structure and thereby facilitate convenient and expeditious installation and servicing thereof.

This object is achieved by combining the switch mechanism with the usual cover plate with which switches are usually provided so that the switch may be installed in its housing or box by simply mounting the plate in position.

An important feature of the invention resides in the switch mechanism itself which, by employing resilient contact arms, is entirely silent in operation.

Some of the advantages of the invention lie in its simplicity as aforesaid, in its adaptability to be embodied in switches of various types and sizes, and in its adaptability to economical manufacture.

With the above more important objects and features in view and such other objects and features as may become apparent as this specification proceeds, the invention consists essentially of the construction and arrangement of parts as shown in the accompanying drawings in which:

Figure 1 is a perspective view of the invention, showing the same as being applied to the switch housing or box in a wall;

Figure 2 is a vertical cross-sectional view of the invention per se;

Figure 3 is a cross-sectional view, taken substantially in the plane of the line 3—3 in Figure 2;

Figure 4 is a group perspective view showing a pair of contact arms used in the invention;

Figure 5 is a cross-sectional view similar to that shown in Figure 2, but illustrating the invention as embodied in a three-way switch rather than in a single pole switch illustrated in Figures 1-4;

Figure 6 is a group perspective view of the contact arms used in the embodiment shown in Figure 5;

Figure 7 is a vertical cross-sectional view, similar to that shown in Figures 2 and 5, but illustrating the invention as embodied in two, combined, single pole switches; and

Figure 8 is a group perspective view of the contact arms used in the embodiment shown in Figure 7.

Like characters of reference are employed to designate like parts in the specification and throughout the several views.

Referring now to the accompanying drawings in detail, more particularly to Figures 1-4, in-

2

clusively, the invention consists of a single pole electric switch designated generally by the reference character 10, this being combined with the usual cover plate 12 with which switches are commonly provided. The cover plate 12 is formed on its rear surface with an integral protuberance or block 14 which is recessed, as at 16 (see Figure 2), to provide clearance for a pair of contact arms 18, 20 and an actuating lever 22, hereinafter more fully described.

The contact arm 18 carries a stationary contact point 24 at one end thereof, while its remaining end portion is provided with a transverse member 18', one end of which, in turn, is equipped with an angulated lug 26 formed with a screw-threaded aperture 28 to receive a terminal screw (not shown) whereby a conductor 30 may be electrically connected to the arm 18, as will be clearly apparent.

The remaining side or end portion of the contact arm member 18' is equipped with an angulated wing 32 terminating in an angulated, sharp-edged flange 34, the member 18' of the arm 18 being mounted on the block-shaped protuberance 14 at one side of the recess 16, and the flange 34 being embedded in the protuberance, whereby the entire arm 18 is firmly secured in position.

The contact point 24 on the arm 18 is adapted to be engaged by a contact point 36 on the aforementioned arm 20, the latter also being equipped with an angulated lug 38 provided with a screw-threaded aperture 40 to receive a terminal screw 42 whereby a second conductor 44 may be electrically connected to the arm 20, as shown in Figure 3. The arm 20 is mounted on the protuberance 14 at the relatively opposite side of the recess 16 with respect to the location of the arm 18, the arm 20 also being provided with a sharp-edged flange 46 which is embedded in the protuberance 14 to firmly secure the arm 20 in position.

It is to be understood that the arm 20, which is preferably arcuated as shown in Figures 2 and 4, is made from resilient material, the resiliency thereof being such that the contacts 24, 36 are normally-separated and the switch is open. However, the aforementioned actuating lever 22, which is pivotally attached to the protuberance 14 by means of a pin 48 and projects outwardly through a slot or opening 50 with which the plate 12 is provided, extends also into the recess 16 and is formed with a cam-shaped head 52, as is best shown in Figure 2. This head engages the adjacent surface of the arm 20 and the configuration of the head is such that when the lever

22 is in its depressed position, as shown in Figures 1 and 2, the contacts 24, 36 are separated, as has been already explained. However, when the lever 22 is pressed upwardly as indicated at 54, the head 52 bears against the arcuate, convex, intermediate portion 56 of the arm 20 and presses the contact 36 against the contact 24, thus closing the switch. It is to be particularly noted that by virtue of the resiliency of the arm 20, the closing and opening of the switch is a silent operation, it being of course understood that the cam-shaped head 52 of the lever 22 will retain the switch in its closed position until the lever is again depressed to the position shown in Figures 1 and 2.

In order to assure silent movement of the lever 22 itself, that is, to prevent the head 52 from impacting against the protuberance 14, a felt washer, or the like, 58 may be interposed between the head 52 and the base of the recess 16, which provision will also prevent foreign matter from entering the switch mechanism through the opening or slot 50.

If desired, a box-shaped enclosure 60 may be applied to the protuberance 14 for the purpose of protecting the switch mechanism, this enclosure being frictionally held in position on the protuberance and being provided with suitable openings, one of which is illustrated at 62 in Figure 3, whereby the conductors 30, 44 may enter the enclosure for connection to the terminals of the switch.

The switch assembly may be installed in a conventional housing or box 64 provided in a wall 66 by simply mounting the cover plate 12 on the wall so that the switch mechanism is disposed in the housing 64. To this end, the cover plate 12 may be formed with a plurality of apertures 68 to receive suitable screws, or the like, whereby mounting of the plate may be effected.

Referring now to the accompanying Figures 5 and 6, these illustrate a modified embodiment of the invention designated generally by the reference character 70 and involving a three-way switch, wherein the cover plate 72 is formed integrally with a protuberance 74, recessed as at 76, while a movable contact arm 78, similar to the aforementioned arm 20, is secured to the protuberance at one side of the recess.

However, the contact arm 78 is provided with two contact points 80, 82, these being disposed at the opposite sides of the arm and being engageable with stationary contact points 84, 86, respectively, provided on respective contact arms 88, 90.

The arms 88, 90 are also secured to the protuberance 74 but at the relatively opposite side of the recess 76 with respect to the location of the arm 78, the arms 88, 90 being mutually spaced and the protuberance 74 being provided with a slot or recess 92 in which the arm 90 may be accommodated, substantially as shown.

If desired, the arms 78, 88, and 90 may be equipped with sharp-edged flanges similar to the aforementioned flanges 34, 46, but, alternatively, such flanges may be omitted and the arms 78, 88 and 90 may be secured to the protuberance 74 by the respective terminal screws 94, 96, 98 with which these arms are provided.

It is to be noted that the free end portion of the arm 78 is disposed between the arms 88, 90, and the resiliency of the arm 78 is such that the contact point 82 is normally urged in engagement with the stationary contact point 86 when the actuating lever 100 is in the position

shown in Figure 5. However, when the lever 100 is tripped, as shown at 102, the contact points 82, 86 are separated, while the contact points 80, 84 are brought together, as will be clearly understood. If desired, an arcuate leaf spring 104 may be mounted on the protuberance 74 by means of the screw 94 which secures the arm 78 in position, the spring 104 pressing against the arm 78 so as to normally maintain the points 82, 86 in contact. In other words, the purpose of the spring 104 is to assist the resiliency of the arm 78 in keeping the points 82, 86 together.

Referring now to the accompanying Figures 7 and 8, these illustrate a further modified embodiment of the invention designated generally by the reference character 110, wherein the cover plate 112 is provided with a protuberance 114 formed with two spaced recesses 116, 118, and an arm 120 is secured intermediate its ends as at 122 to the protuberance 114 between the recesses 116, 118.

One end portion of this arm is resilient and is provided with a contact point 124 which is engageable with a stationary contact point 126 on a stationary arm 128 secured to the protuberance 114, as at 130, while the remaining end portion of the arm 120 is relatively non-resilient and carries a contact point 132. The latter is engageable with a contact point 134 on a resilient arm 136 which is secured to the protuberance 114 as at 138, and a pair of independently actuatable levers 140, 142 are provided on the plate 112, the lever 140 being engageable with the resilient end portion of the arm 120 which carries the point 124, while the lever 142 is engageable with the arm 136 carrying the point 134. The resiliency of the arms 120, 136 is such that the points 124, 126 and 132, 134 are normally separated, but may be selectively and individually closed by simply actuating the respective levers 140, 142, as will be clearly apparent. In this manner, electric current delivered to the terminal 122 may flow selectively to either or both the terminals 130, 138, whereby the device performs the function of two combined single-pole switches.

It is believed that the advantages and use of the invention will be readily apparent from the foregoing disclosure, and accordingly, further description thereof at this point is deemed unnecessary.

Having described the invention, what is claimed as new is:

For use in electrical systems, an outlet box adapted to be positioned in a wall and having an open side, a wall plate of electrical insulating material closing the open side of the box and adapted to be secured to a wall, said plate having an integral body projecting laterally from the plate which is received in the box, said body having a recess which opens into the box, electric switch means in the recess operable from the side of the plate opposite said body comprising a fixed contact carried by the body at one side of the recess and a movable contact carried at the other side of the recess for engagement with the fixed contact, means for yieldingly urging the contacts into engagement, said plate having an opening therethrough communicating with the recess, a lever extending through the opening and pivoted intermediate its ends to the body, said movable contact having an arched surface normally disposed in the path of the inner end of the lever whereby pivotal movement of the lever in one direction separates the contacts, cam means adjacent the inner end of the lever asso-

ciated with the movable contact to cause a snap action in the movement of the lever, combined means in the recess preventing passage of foreign matter through the opening and also limiting and cushioning pivotal movement of the lever, a protective cover in the box embracing and frictionally retained on the body, said box and cover being spaced and the cover having an aperture therethrough permitting connection of an electrical conductor to the switch means.
